HERMETIC SEAL FOR BOTTLES

Chisada Ohta, Kita-Ku, Osaka, Japan

Application March 16, 1932, Serial No. 599,253,
and in Japan March 23, 1931

3 Claims. (Cl. 215—39)

The invention relates to improvements in closures of the double-closure type, so to speak, or closures having, in addition to the ordinary plug, such as, of cork, a secondary device for insuring a complete seal of the mouths of bottles; and the object of this improvement is to provide a closure consisting broadly of a cap-shaped metal structure, having a cylindrically extended flange to attach securely to the neck of the bottle. The top of the cap-shaped metal structure may be embossed and under certain circumstances formed with a circular opening in the centre, while the cylindrically extended flange or more particularly cylindrical body is provided with two linear projections or embossments, upper and lower, belting the cylindrical body in annular forms, and with a number of elliptical perforations arranged upright and at certain intervals between the horizontal annular embossments.

Closures of the double-closure type have been proposed as having a cork plug fitted with an encircling brim to rest, preferably with a washer of suitable material, on the top of the mouth of the bottle, while the body of the plug is placed in the neck of the bottle. To insure a double closure, the mouth of the bottle wherein the body of the plug is fitted is crowned with a metal cap having an extended edge portion provided with corrugations by means of which the metal cap is to be secured to the mouth of the bottle.

With the closures of the double-closure type referred to, the common drawback is the fact that the metal cap cannot be secured to the bottle-neck with satisfactory tightness. It appears that the defects are due, partly, to the fact that the thickness the brim referred to, as well as the height to which the body of the plug protrudes through the brim, are indefinite, and, partly, to the fact that the corrugated flange of the metal cap does not bend down deep into the encircling groove provided on the bottle-neck. As a result, the closures cannot withstand the expanding forces arising in bottled liquids of certain kinds and are from time to time removed spontaneously from the mouths of the bottles.

Further, stoppers embodying the described drawbacks are at all times subject to removal from incorrect motives, since they are capable of being detached from and attached to the mouths of the bottles with ease and with simple tools.

According to the present invention, the cylindrical body or cylindrically extended flange of the cap-shaped metal structure extends, when applied to the mouth of the bottle, far beyond

or below the annular projection on the neck of the bottle and adheres closely to the surface of the bottle-neck, while its perforated zone is closely gathered and deeply set in the groove just beneath the annular projection, aforesaid. The lowermost portion or edge portion of the cylindrical body does not permit of the application of extractors, by reason of its tight attachment to the bottle-neck, and therefore the invention proposes to provide a lug on the edge portion of the cylindrical body, so that by pulling the lug the cap-shaped structure may be broken and stripped from the mouth of the bottle.

The present invention embraces, as a modification, a construction in which the top of the cap-shaped structure has on its inside a cork disc to mount the periphery of the mouth of the bottle and thereby insure a perfect joint with the bottle-mouth. Obviously this type of construction does not necessitate the use of the plugs.

The invention is further described with reference to the accompanying drawing, in which:

Fig. 1 is a perspective view of the closure with a part in section, the top of the cap-shaped metal structure being shown as having an opening;

Fig. 2 is an elevational, partly sectional, view of the closure of Fig. 1, the cap-shaped metal structure being shown capping a cork-plug fitted in the mouth of a bottle and having a metal top-covering;

Fig. 3 is an elevational, partly sectional, view of another form of the closure, the cap-shaped metal structure being shown having no opening in the top but embossed so as to cap the plug inserted in a bottle;

Fig. 4 is an elevational, partly sectional, view of the closure of Fig. 3, shown secured in position on the mouth of a bottle;

Fig. 5 is an elevational view of a modified form of the closure which has a cork disc on the inside of the top of the structure so as to cap the mouth of a bottle direct; and

Fig. 6 is an elevational, partly sectional, view of the closure of Fig. 5, shown placed in position on the mouth of a bottle.

Similar numerals denote similar parts throughout the several views.

The closure consists broadly of a cap-shaped metal structure having a cylindrically extended flange or cylindrical body 1. About the middle portion of the cylindrical body are formed two annular projections or embossments 2 and 3, horizontally encircling the cylindrical body and parallel to each other. Between these horizontal

tal annular embossments 2 and 3 are provided a number of elliptical perforations 4 arranged with their major axes upright and at certain intervals. Beneath the lower horizontal annular 5 embossment 3 extends the lowermost or edge portion 1' of the cylindrical body, from which depends a lug 7. The top 6' of the cap-shaped metal structure is normally cut out so as to leave a round opening 6, as shown in Fig. 1, in order 10 that the head of the plug c may protrude through the opening so that the marginal portion of the top 6' surrounding the opening can rest on a brim a fitted around the plug. Under certain 15 circumstances, the top 6' of the cap-shaped metal structure is not cut out, but in turn should be properly embossed so as to surmount the head of the plug, (see Figs. 3 and 4). It is to be noted that the plug c is protected by a metal covering b which not only extends over the head of the plug 20 but extends down to the lower edge of the brim a fitted around the plug, thereby securing the brim to the plug proper.

To attach the closure to the mouth of a bottle, it is necessary to place the upper horizontal annular embossment 2 of the cylindrical body into registry with the glass projection B around the mouth of the bottle. When pressed by a machine, such as is used in connection with "crown corks", the annular embossment 2 is stretched 30 out, causing the perforated zone A to fall into the groove D just beneath the glass projection B on the bottle-neck. The seating of the perforated zone A takes place by virtue of the novel arrangement of the horizontal embossments and 35 perforations therebetween as described. Therefore, in spite of the pressure exerted on the upper horizontal embossment 2, the perforated zone A does not travel downwards along the surface of the bottle-neck, but falls into the groove D. 40 The compression of the perforated zone causes the lowermost or edge portion of the cylindrical body to become attached securely to the neck of the bottle. The even and tight attachment of

the edge portion of the cylindrical body to the surface of the bottle-neck prevents any tools of ordinary description from taking hold of the closure with a view to removing same from the bottle. To provide for the removal of the closure, the edge portion 1' of the cylindrical body is formed with a lug 7 so that by pulling the lug one can strip the stopper off the bottle.

Figs. 5 and 6 illustrate a modified form of the closure, in which the top of the cap-shaped metal structure, which has no opening but is embossed, is lined with a disc of proper material, such as cork, and thereby adapted to rest on the mouth of a bottle, thus affording by itself a means of perfect closure. Obviously, in this form of the closure the plug c is dispensed with.

I claim:

1. A closure for bottles, having mouths with outwardly projecting lips, consisting of a cap-shaped metal structure adapted to rest on the mouth of a bottle, and having a cylindrically extended body, with two annular embossments horizontally encircling the middle portion of the cylindrical body, one above the other, and with an intervening zone having a number of perforations located at intervals apart, whereby upon compression of the uppermost of said embossments, in applying said closure to a bottle, the perforated zone will be forced into the space below the lip of the bottle mouth, and thereby tightly secure the closure to the neck of the bottle.

2. A closure for bottles as claimed in claim 1, wherein the perforations provided between the horizontal annular embossments are shaped in the form of an ellipse, substantially as described.

3. A closure for bottles as claimed in claim 1, wherein the lowermost portion of the cylindrical body is provided with a lug extending from said portion, substantially as described.
